(57) **CLAIM**

The ornamental design for an electronic filter element, as shown and described.

DESCRIPTION

FIG. 1 is a front, left, top perspective view of an electronic filter element, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the enlarged scale thereof; and,

FIG. 8 is a bottom plan view of the enlarged scale thereof. The dashed broken lines in the figures are for the purposes of illustrating portions of the electronic filter element that form no part of the claimed design.
